UNITED STATES PATENT OFFICE.

JOHN P. ANDERSON, OF DENVER, COLORADO, ASSIGNOR OF ONE-THIRD TO EMIL PETERSON, OF DENVER, COLORADO.

ARCH-SUPPORT FOR SHOES.

1,134,804.

Specification of Letters Patent.

Patented Apr. 6, 1915.

Application filed August 4, 1914. Serial No. 855,010.

To all whom it may concern:

Be it known that I, JOHN P. ANDERSON, a citizen of Sweden, (with first papers in United States,) residing at Denver, in the county of Denver and State of Colorado, United States of America, have invented certain new and useful Improvements in Arch-Supports for Shoes; and I do hereby declare the following to be a full, clear, and exact description of the invention, such as will enable others skilled in the art to which it appertains to make and use the same.

This invention relates to resilient arch supports for shoes and has for an object to provide a resilient support which shall be securely, but not rigidly, mounted at both ends.

Another object is to provide, in a device of the class described, support retaining members which shall securely retain the resilient supporting member in desired position when in use but still permit the ready removal and replacement of the supporting member when desired without change in or interference with the retaining members.

With these and other objects in view the invention comprises certain novel construction, combinations and arrangements of parts as will be hereinafter more fully described and claimed and as illustrated in the accompanying drawings in which similar characters of reference indicate corresponding parts throughout the several views and in which—

Figure I. is a side elevation of a shoe with my invention in place thereon, a portion of the heel of the shoe being cut away in order to expose the entire invention to view. Fig. II. is a plan of the bottom of a shoe with my support attached, showing a portion of my invention in dotted lines. Fig. III. is a side view of my invention showing the detail thereof and showing a section of the socket on line A—A in Fig. II. Fig. IV. is a detail of the connection between the spring and the rear support.

My invention consists of three parts, a front fastening or socket member 1 attached to the under side of the arch 2 of the shoe at the forward and lower part thereof by suitable means as nails 3, a spring 4 having one end slidingly mounted in said member and having its other end hooked as at 5 and having a lug 6 thereon, and a rear fastening

comprising a strip 7 hooked as at 8 for engaging hook 5 and having an opening 9 for engaging lug 6.

Strip 7 is slidably mounted in the heel of the shoe preferably at its point of juncture with the shoe as shown at Fig. I., a suitable socket cut in the heel as at 10 for the reception of strip 7 being all that is required for such mounting, or strip 7 may simply be driven in between the heel and the shoe being pointed as at 7^a for that purpose.

It will be noted that spring 4 is so bent that the end thereof carrying the hook 5 stands away from the shoe sole or arch as at 11 and hook 8 is offset below the body of strip 7 sufficiently to permit spring 4 to

thus stand away to such distance that the space between the shoe sole or arch and spring 4 at 11 is slightly in excess of the length of lug 6. It follows that when the spring is raised against the shoe, closing the space at 11, lug 6 will be withdrawn from opening 9 and spring 4 may be moved side-

wise in either direction until hook 5 is moved beyond and thus disengaged from hook 8 when pressure on its other end may be released and spring 4 may be drawn from socket member 1. Conversely the spring is put in position by inserting the end into socket member 1, raising the hooked end 5 and sliding it into hook 8, and releasing the pressure; whereupon the spring action causes it to stand away from the shoe and causes lug 6 to engage opening 9 as shown in the drawings. By this construction I avoid at-

taching the support to the shoe by rigid means which either tear out or else interfere with the elasticity of the support. I also provide a support which is simple and easily attached to any shoe.

It will be noted that the spring 4 may be readily removed and replaced as above described. This is a great advantage. It often happens that a person with a broken down arch can at first, during cure of the same, wear a support only slightly arched, but as the treatment continues he can wear a support arched more and more. My invention meets this condition by providing simple means for changing the spring support 4 without changing any other portions of the device, or the spring may be taken out and bent so as to have an arch of a less radius and then replaced. In this way exact

adjustment of the support to the conditions existing in each case can be easily and quickly made.

It will be evident that should the sole of the shoe be so bent as to cause the spring 4 and hook 5 to draw upon hook 8, no injury can be done thereby to the shoe or to the supporting device for the reason that such action will result in drawing strip 7 forward in and partly out of its socket 10 in the heel and so holding it until the shoe resumes its normal position as shown in the drawings when the pressure of spring 4 and hook 5 against hook 8 will force strip 7 back to its normal position as shown in the drawings.

As clearly shown in the drawings, spring 4 is formed to normally follow the line of and press against the under side of the arch of the shoe, thus supporting the same, except where it stands away leaving space at 11 as above described. Conversely any weight upon the arch will tend to depress or flatten the spring 4 and project the end thereof farther into socket member 1.

It will be noted that the front end of the socket member 1 is closed by a wall 1^a which acts as a stop for the end of spring 4, and it will be apparent that when the end of spring 4 strikes this wall, the opposite end being positioned in hook 8 and thus braced against the heel, further depression or flattening of the spring 4 will be impossible so that the extent of the depression of spring 4 may be governed by the position of socket member 1, greater depression being permitted the farther forward the socket member is placed with relation to the normal position of the end of spring 4 therein.

I claim:

1. An arch support for shoes comprising a socket member secured beneath the arch near the front end of the latter, a spring support of normally greater curvature than the arch with its front end inserted in said

member and its rear end spaced slightly below the arch, and a rear fastening device carried by the heel and with which the rear end of said spring support is detachably connected.

2. An arch support for shoes comprising a socket member secured beneath the arch near the front end of the latter, a spring support of normally greater curvature than the arch with its front end inserted in said member and its rear end spaced slightly below the arch and bent downward into a hook, and a strip attached to the heel and having its front end bent upward into a hook adapted to removably engage the hook on the spring support.

3. An arch support for shoes comprising a socket member secured beneath the arch near the front end of the latter, a spring support of normally greater curvature than the arch with its front end inserted in said member and its rear end spaced slightly below the arch and bent downward into a hook-shaped rear end, the bill of the hook having a downwardly projecting lug, and a strip inserted in the heel and having its front end bent upward into a hook whose throat is disposed beneath the bill of the hook on the spring support and provided with an opening for the reception of said lug.

4. In a device of the class described, a spring support, a socket member for receiving one end of said spring support, and a second member for engaging the other end of said spring support, said spring support and second member being arranged to be held in such engagement normally by the tension of said spring support and to be disengaged by depression of its last-named end.

In testimony whereof I affix my signature in presence of two witnesses.

JOHN P. ANDERSON.
